Rex Frye.
ATTORNEY.

UNITED STATES PATENT OFFICE.

GEORGE K. PARSONS, OF DETROIT, MICHIGAN.

ADVERTISING DEVICE.

Application filed April 7, 1922. Serial No. 550,385.

To all whom it may concern:

Be it known that I, GEORGE K. PARSONS, a citizen of the United States, and residing at Detroit, county of Wayne, and State of Michigan, have invented a new and Improved Advertising Device, of which the following is a specification.

This invention relates to improvements in advertising devices and has for its principal object the provision of a moving belt adapted to carry a changeable sign or series of signs which will be repeatedly displayed through an illuminated window at the front of the advertising device.

Another object of my invention is to provide automatic tensioning means for the moving belt whereby it will be maintained in taut condition throughout its entire length and enable portrayal at the window of the advertising device as a smooth continuous sign.

Another object of my invention is to provide a frictional drive mechanism for moving the belt constructed and arranged to automatically maintain the friction producing parts in proper contact.

The above and other objects of my invention will be apparent from the following description wherein reference is made to the accompanying drawings illustrating preferred embodiments of my invention, and wherein similar reference numerals designate similar parts throughout the several views.

35 In the drawings:—

Fig. 1 shows my improved advertising device in position for display within a store window;

Fig. 2 is a sectional view showing an adaptation of my advertising device on a wall or store front whereby it can be read from three directions;

Fig. 3 is a cross sectional view taken substantially on the line 3—3 of Fig. 4;

Fig. 4 is a horizontal sectional view taken substantially on the line 4—4 of Fig. 5, and

Fig. 5 is a vertical sectional view taken substantially on the line 5—5 of Fig. 4.

Referring now to the drawings the numeral 5 designates a store window of the usual or any desired type within which is arranged my improved advertising device with its front wall 6 facing the front of the store window. The front wall 6 is preferably formed with a display opening 7

through which may be viewed the forward extremity of a traveling belt 8 on which may be marked any desired sign or display for advertising or instructive purposes. The belt 8 is preferably formed as an endless belt of substantially great length, passing over a series of side rollers 9 and 10 journaled in the horizontal portions 11 of the side crossbars of the frame work of my advertising device. These crossbars are preferably formed of L-shaped structural metal horizontally spaced adjacent the upper and lower extremities of the device by longitudinal front and rear bars 13, and vertically spaced by a series of supports 13^a. The side rollers 9 and 10 are preferably formed with upper and lower flanges 14 arranged to guide the belt as it passes around the rollers and prevent it from accidentally slipping from its desired position. All rollers which contact the face of the belt bearing the message displayed are constructed substantially as shown in Fig. 3, with their center portions reduced in diameter to avoid accidental erasing of the message as the belt travels.

To provide an automatic tension upon the endless belt 8 so that it will always be held taut I preferably mount one or more tensioning rollers 15 in a pair of spaced levers 16 pivoted at their rear extremities, as at 17, upon central crossbars 18 secured to the upper and lower side crossbars 11 of the framework. Adjacent their free ends the levers 16 are joined by a vertically disposed rod 19, which rod is preferably formed substantially centrally of its length with an apertured ear 20 in which is secured one extremity of a tensioning spring 21. The spring 21 tends to swing the levers 16 on their pivots so as to exert a tension upon the endless belt 8 where it passes over the tensioning rollers 15, which tension is transmitted throughout the entire length of the belt.

The opposite end of the tensioning spring 21 is secured to the pivoted bracket 22 carrying the pressure roller 23 of the belt driving device (see Figs. 4 and 5). The pressure roller 23 is journaled within the upper and lower arms of the bracket 22, which arms are pivoted intermediate their ends upon the shaft 24 secured substantially centrally of the upper and lower plates 25, and the spring 21 is secured in the cross member connecting the upper and

lower arms of the bracket 22. The pressure roller 23 is slightly shorter than the side rollers 9 and 10 and the drive roller 26 and serves to press the belt 8 firmly 5 against the drive roller 26 through the tension exerted by the spring 21. It will be noted that the tensioning spring 21 is thus given a double function, to wit, to provide a constant tension on the rollers 15 to maintain 10 the endless belt 8 in taut position, and also press the roller 23 firmly against the belt 8 where it passes over the drive roller 26.

The drive mechanism for the belt 8 comprises 15 a motor 27 of any desired type mounted upon a base plate 28 fixed upon a bracket 29 pivoted, as at 30, within the supporting bracket 31. With this construction the weight of the motor itself tends to 20 swing the bracket plate 29 on its pivot, and this is used, as hereinafter described, to maintain a positive frictional engagement between the motor and the remaining elements of the driving mechanism. A small 25 friction roller 32 is fixed at the extremity of the projecting shaft 33 of the motor with its periphery in contact with the upper face of the frictional disc 34 which is fixed on the shaft 24 extending between 30 the upper and lower bracket plates 25 (see Fig. 5). On the same shaft 24, immediately above the friction disc 34, is fixed a pinion 35 arranged to mesh with a gear 35 wheel 36 fixed on the same shaft 37 which 35 carries the driving roller or drum 26.

In operation when the motor is set in motion by throwing an appropriate switch (not shown) the friction roller 32 will be rotated at the same speed as the motor and 40 will drive the friction disc 34 and pinion 35, the rate of rotation of the pinion being reduced in accordance with the size of the friction disc and the distance of the point of engagement with the friction roller from 45 the center of the friction disc. The rotation of the pinion 35 is in turn imparted to the gear wheel 36 and the drive roller 26, the rate of rotation of the drive roller being lessened in proportion to the number 50 of gear teeth in the gear wheel 36 to those in the pinion 35. It will be noted that I have thus arranged a multiple series of reducing gears whereby an ordinary commercial motor can be driven at its usual speed 55 imparted by currents in every day use without moving the belt 8 at a speed that will prevent easy reading of the signs displayed thereon. The rotation of the drive roller 26 will move the endless belt 8 in the direction desired, the pressure roller 23 engaging the belt on the face opposite to that contacting the drive roller and serving to maintain a positive frictional contact between the belt and drive roller. As the 60 belt is driven it passes the display opening

7 of my advertising device through which may be read the advertising or instructive signs carried by the belt 8.

I preferably construct the belt 8 of a flexible black material, such as pantasote, 70 which can be written upon with white chalk or the like, or can be made the background for removable display letters, pictures, or the like. In arranging the message to be displayed through the medium 75 of the belt the words may be written upon the surface of the belt with white or colored chalk at the rear of the advertising device, the belt being arranged so that it will advance from right to left to one 80 facing the rear of the advertising device, the same as when facing the front of same. The belt may be advanced by hand during the writing of the message, or the motor may be set in motion to produce a proportional advance as desired. When it is desired to change the message displayed, it is only necessary to erase the former message by wiping off the chalk or removing the letters or pictures secured upon the 85 belt, whereupon a new message can be arranged upon the surface of the belt as desired. Suitable lamps 38 may be arranged in rear of the display opening 7 in position to cast their luminous rays upon the belt 90 as it passes across the display opening.

In Fig. 2 I have illustrated an embodiment of my invention whereby the message may be read from three directions. The rollers 9^a which guide the endless belt 8^a 100 are arranged in a substantially semi-circular relation and are spaced a desired distance behind a semi-circular transparent member 49. The same drive mechanism, tensioning means, etc., may be employed and 105 the belt 8^a driven so as to pass over the rollers 9^a from right to left. Accordingly the message upon the belt may be read by persons standing directly in front of the device or at either side thereof, and persons 110 walking by the building on which the advertising device is displayed may continue to read the message without stopping.

While it will be apparent that the illustrated embodiments of my invention herein 115 disclosed are well calculated to adequately fulfill the objects and advantages primarily stated, it is to be understood that the invention is susceptible to variation, modification and change within the spirit and 120 scope of the subjoined claims.

Having described my invention, I claim:

1. In a device of the character described, a frame having a display opening therein, 125 a series of guide rollers journaled in the frame, a drive roller, an endless belt arranged to travel over said rollers and past the display opening, means for rotating the drive roller, and means for maintaining the 130

- belt in taut condition, comprising a tensioning roller over which the belt passes, a pivoted rod in which the tensioning roller is journaled, a tensioning spring secured to 5 said rod and adapted to swing the rod and tensioning roller to take up all slack in the endless belt, a pressure roller arranged to hold the belt in contact with the drive roller, a pivoted bracket in which the pressure 10 roller is mounted, and means whereby the tensioning spring may be secured to said bracket to urge the pressure roller toward the drive roller.
2. In a device of the character described, 15 a frame having a display opening therein, a series of guide rollers journaled in the frame, a drive roller, an endless belt arranged to travel over said rollers and past the display opening, means for rotating the 20 drive roller, comprising a gear wheel fixed on the same shaft as the drive roller, a pinion meshing therewith, a friction disc fixed on the same shaft as the pinion, a friction roller engaging the upper face of the friction disc, a motor having a projecting shaft 25 on which the friction roller is secured, and means for mounting the motor whereby the weight of the motor will maintain the friction roller in contact with the friction disc.
3. In a device of the character described, 30 a frame having a display opening therein, a series of guide rollers journaled in the frame, a drive roller, an endless belt arranged to travel over said rollers and past the display opening, means for rotating the 35 drive roller, comprising a gear wheel fixed on the same shaft as the drive roller, a pinion
- ion meshing therewith, a friction disc fixed on the same shaft as the pinion, a friction roller engaging the upper face of the friction disc, a motor having a projecting shaft on which the friction roller is secured, a plate for supporting the motor pivoted upon the frame whereby the weight of the motor will press the friction roller 40 into engagement with the friction disc.
4. In a device of the character described, 45 a frame, a series of guide rollers journaled in the frame, a drive roller, an endless belt arranged to travel over said rollers, a gear 50 wheel secured on the same shaft as the drive roller, a pinion meshing with the gear wheel, a friction disc mounted on the same shaft as the pinion, a friction roller engaging the friction disc, a motor having a projecting shaft on which the friction roller is secured, 55 a series of tensioning rollers over which the belt is adapted to travel, pivoted rods in which the tensioning rollers are journaled, a pressure roller arranged to press the belt 60 against the drive roller and mounted in a pivoted bracket, and a spring connected at its opposite ends to said bracket and the rods carrying the tensioning rollers whereby the pressure roller is urged toward the drive 65 roller and the tensioning rollers are moved to positions taking up all slack in the endless belt.

In witness whereof I hereunto set my hand.

GEO. K. PARSONS.
